UNITED STATES PATENT OFFICE

2,586,102

DOOR OR WINDOW FRAME

Arthur J. Smith, Cleveland, Ohio

Application March 30, 1948, Serial No. 18,028.

3 Claims. (Cl. 20—11)

1

The invention relates to improvements in door or window frames.

One of the objects of the invention is the provision of a formed strip of metal or other sheet material strong in tension so constructed as to be adapted for rapid installation, functioning to close the counterbalancing weight-well in the case of a window frame, bracing the frame from the studding on that side of the frame and constituting a holder for the lathing material, such as wooden lath or wallboard, where it adjoins the stile.

Another object is the utilization of sheet material means for sealing the joint between the inner wall and the stile to prevent cold air from entering there in the winter time and to prevent the admission of dust or soot-laden air which would soil the surface of the wall adjacent the frame.

Other objects and features of novelty will appear as I proceed with the description of that embodiment of the invention which, for the purposes of the present application, I have illustrated in the accompanying drawing, in which

Fig. 1 is a fragmental elevational view of one side of a window frame and the adjacent portion of a building wall illustrating an embodiment of the invention.

Fig. 2 is a horizontal sectional view taken substantially on the line 2—2 of Fig. 1.

In the drawing a window jamb or side stile constituting part of a window frame is shown at 10. Suitably connected with the outer edge of stile 10 there is a blind stop 11. 12 and 13 are wall studs. The outer part of the wall may be of any standard construction, and as illustrated herein consists of sheathing 14, building paper 15 and siding 16. The lower sash 17 of the window is arranged to slide between a parting strip 18 secured to stile 10 and a front stop 19 also suitably secured to the stile. One side only of the frame is illustrated, it being understood that the other side may be identical therewith except for rights and lefts. In the case of a window frame the space 20 between stile 10 and wall stud 12 may serve as a well in which counterbalancing weights 21 are accommodated.

On one side adjacent its inner edge stile 10 is preferably provided with a rabbet 22 to constitute a seat for a formed strip of sheet metal or other sheet material strong in tension. This strip may be said to be F-shaped in cross-section, the top portion 23 of the F being considerably extended so as to bridge the space 20 and overlie at least a part of the stud 12. A portion 24 of the strip

5 at right angles to the portion 23 is of a width to extend forward to a point flush with the inner surface of stile 10, where it is folded upon itself to form a rebent portion 25, the latter terminating in a flange 26 parallel with portion 23 and hereinafter termed the intermediate part of the F. Suitable fastenings 27 disposed at intervals along the length of the strip extend through aligned holes 9 in the portions 24 and 25 thereof 10 and enter the stile 10. These fastenings together with the rabbet 22 serve to firmly anchor the strip upon and against the stile. The portion 23 of the strip is secured to the stud 12 as by means of nails 28 spaced along its length. The formed strip extends of course throughout the height of the frame so as to completely close and seal the inner side of well 20.

The short intermediate flange 26 of the strip is spaced from the portion 23 thereof just far 20 enough to receive rather snugly the adjoining part of the lathing material 30, illustrated herein as wallboard. Wooden lath, expanded metal or other material for the same purpose could be substituted of course. This lathing material is 25 pressed into the space behind flange 26 and is then secured to the studding by suitable means such as nails 31. Thereafter one or more layers of plaster 32 are applied to the lathing to present a surface flush with the inner surface of stile 10 30 and the rebent edge between portions 24 and 25 of the strip. The holes 9 are spaced two or three inches apart while the screws 27 are spaced about six inches apart, the holes between screws serving as anchors or keys for the plaster.

35 A good joint is thereby obtained between the inner wall and the stile 10. However the joint may be concealed if desired by a finish molding 33 secured to the stile by nails 34 and overlapping somewhat the bent edge of the strip and its joint with the plaster 32.

The formed strip herein disclosed is strong in tension, and being employed on both sides of the frame, ties the same firmly to the studding. The frame is thus well braced. The joint between the inner wall and the frame is also thoroughly sealed, and the lathing material is 45 securely attached to the stile. Furthermore the mounting of the formed strip is quickly and easily effected.

While the rabbet 22 is desirable as locating accurately the right angle portion of the strip and providing a firm seat for the same, it may be omitted in some cases, in which event the right angle portion 24 of the strip would lie against

the side stile 10, its front edge being caused to lie flush with the front surface of the stile.

Having thus described my invention, I claim:

1. A frame for a window or the like, comprising a side stile, a wall stud cooperating therewith and spaced therefrom to provide a well for counterbalancing weights, a strip of sheet material strong in tension connected with said wall stud and extending to said stile for closing the inner side of said well, said sheet material having a right angle portion attached to said stile and a return bend flush with the inner surface of the stile terminating in a flange parallel with the first mentioned portion of said strip and spaced therefrom to receive lathing material, said flange being spaced from the line of the bend a distance corresponding to the proposed thickness of a plaster coating, and from the main portion of said sheet material a distance corresponding to the thickness of said lathing material whereby the said lathing material may be caused to extend into the angle of said sheet material and may be fastened to said stud, thereby reinforcing that part of the sheet material which extends across said well.

2. A frame for a window or the like, comprising a side stile, a wall stud cooperating therewith and spaced therefrom to provide a well for counterbalancing weights, a strip of sheet material strong in tension connected with said wall stud and extending to said stile for closing the inner side of said well, said sheet material having a right angle portion attached to said stile and a return bend flush with the inner surface of the stile terminating in a flange parallel with the first mentioned portion of said strip and spaced therefrom to receive lathing material, said flange being spaced from the line of the bend a distance corresponding to the proposed thick-

ness of a plaster coating, and from the main portion of said sheet material a distance corresponding to the thickness of said lathing material, said stile being rabbeted to receive the said right angle portion of said strip.

3. A frame for a window or the like, comprising a side stile, a wall stud cooperating therewith and spaced therefrom to provide a well for counterbalancing weights, a strip of sheet material strong in tension connected with said wall stud and extending to said stile for closing the inner side of said well, said sheet material having a right angle portion attached to said stile and a return bend flush with the inner surface of the stile terminating in a flange parallel with the first mentioned portion of said strip and spaced therefrom to receive lathing material, said flange being spaced from the line of the bend a distance corresponding to the proposed thickness of a plaster coating, and from the main portion of said sheet material a distance corresponding to the thickness of said lathing material and a vertical molding secured to the inner surface of the stile overlapping said return bend.

ARTHUR J. SMITH.
